(57) **CLAIM**

The ornamental design for a retread band, as shown and described.

DESCRIPTION

FIG. 1 is a perspective view of a segment of a retread band showing our new design;

FIG. 2 is a front elevation view of a segment of the retread band of FIG. 1;

FIG. 3 is a portion taken from FIG. 2 to show the section line for FIG. 4; and,

FIG. 4 is a section view of the retread band taken along line A-A of FIG. 3.

The broken lines in the drawing depict unclaimed environment and form no part of the claim.
